Primary Examiner — Daniel J Domino*Assistant Examiner* — Samina Vieth(74) *Attorney, Agent, or Firm* — Birchwood IP(57) **CLAIM**

The ornamental design for a wireless presenter, as shown and described.

DESCRIPTION

FIG. 1 is a front, right and top perspective view of a wireless presenter, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is a front, right and top perspective view of a wireless presenter in an alternate configuration.

The broken lines shown in the drawings illustrate portions of the wireless presenter that form no part of the claimed design.
